COMBINATION GAS LIGHTER AND FILLER SET

Charles T. Breitenstein, Chicago, Ill., assignor to Raymond T. Maloney, Chicago, Ill.

Application March 21, 1955, Serial No. 35,116

Term of patent 14 years

(Cl. D48—27)

FIG. 1

FIG. 2

FIG. 3

FIG. 4

Fig. 1 is a front elevational view of a combination gas lighter and filler set, showing my new design;

Fig. 2 is a bottom plan view of the same;

Fig. 3 is a top plan view of the same;

Fig. 4 is a side elevational view of the same.

I claim:

The ornamental design for a combination gas lighter and filler set, as shown.

No references cited.

UNITED STATES PATENT OFFICE
CERTIFICATE OF CORRECTION

Design No. 177,893

June 5, 1956

Charles T. Breitenstein

It is hereby certified that error appears in the above numbered patent requiring correction and that the said Letters Patent should read as corrected below.

The name of the assignee was erroneously described and specified as "Raymond T. Maloney" whereas said name should have been described and specified as -- Raymond T. Moloney --.

Signed and sealed this 14th day of August 1956.
